UNITED STATES PATENT OFFICE.

WILLOUGHBY MOFFAT, OF HAMILTON, ONTARIO, CANADA.

MOP-WRINGER.

No. 909,442.

Specification of Letters Patent.

Patented Jan. 12, 1909.

Application filed August 6, 1907. Serial No. 387,351.

To all whom it may concern:

Be it known that I, WILLOUGHBY MOFFAT, subject of the King of Great Britain, residing at Hamilton, in the district of Wentworth, 5 Province of Ontario, Canada, have invented certain new and useful Improvements in Mop-Wringers, of which the following is a specification.

The present invention relates to certain 10 new and useful improvements in mop wringers of that type which embody a pair of co-operating rollers designed to be mounted upon a suitable receptacle so as to grip a mopcloth between the same.

15 The object of the invention is to design a simple and inexpensive mop wringer of this character and the invention contemplates novel means for mounting the fixed roller and guiding the mop into contact with the same, 20 and a novel treadle mechanism for operating the movable roller.

For a full description of the invention and the merits thereof and also to acquire a knowledge of the details of construction and 25 the means for effecting the result, reference is to be had to the following description and accompanying drawings, in which:

Figure 1 is a perspective view of a pail having the mop wringer applied thereto. Fig. 2 30 is a vertical sectional view through the same, the rollers being shown as moved into an operative position. Fig. 3 is a top plan view of the same. Fig. 4 is an enlarged detail view of one of the inner brackets upon which the 35 fixed roller is journaled. Fig. 5 is a similar view of one of the outer brackets upon which the swinging frame is mounted. Fig. 6 is a sectional view through one of the outer brackets upon which the swinging frame is 40 mounted.

Corresponding and like parts are referred to in the following description and indicated in all the views of the drawings by the same reference characters.

45 The mop wringing device may be applied to any suitable receptacle such as the pail 1 which is of the conventional construction. The fixed roller 2 is arranged within the mouth of the receptacle 1 preferably slightly 50 to one side of the same and is journaled upon the inner brackets 3 secured to the interior of the pail adjacent the upper edge thereof. Each of these inner brackets 3 comprises a body portion which is rigidly connected to 55 the inner face of the pail by any suitable fastening means such as the bolts 4, and a later-

ally extending wing 5 which projects over the upper edge of the pail and is preferably located immediately over the opening 6 which serves as a bearing for the pin at the 60 end of the roller 2. It will also be observed that an inwardly extending guide flange 7 is formed in conjunction with each of the inner brackets 3, the said guide flanges having their inner edges inclined and serving the 65 double function of guiding a mop cloth into contact with the fixed roller and preventing the same from slipping around the ends of the roller and being wound upon the pivot pins thereof. Projecting upwardly from 70 each of the inner brackets 3 is an integral ear 8, the said ears being slightly offset from the interior walls of the receptacle and serving as a means for securing a bail 9 of the usual construction thereto. 75

The movable roller 10 is somewhat greater in length than the width of the receptacle 1 and is journaled upon a foot actuated swinging frame. A spring normally holds the movable roller in the position shown in Figs. 80 1 and 3 in which a comparatively large space exists between the two rollers, the said space permitting the mop to be readily inserted within the pail or placed in position against the fixed roller for being wrung when the 85 movable roller is brought into contact therewith. This swinging frame comprises the upright arms 11 carrying the movable roller 10 and the lateral arms 12 which are made rigid with the upright arms by any suitable 90 means such as the braces 13 and are connected by an arched cross piece 14 carrying a foot piece 15. Outer brackets 16 are secured to the exterior of the receptacle 1 and are formed with stub shafts 17 upon which 95 the swinging frame is mounted. Enlargements are located at the base of the stub shafts 17 and the said enlargements are surrounded by coil springs 18, one of the ends of each of the springs engaging a lug 19 upon 100 the bracket while the opposite end is hooked as indicated at 20 and engages the upright arm 11 of the swinging frame. As has been previously mentioned these springs operate to hold the movable roller 10 spaced from the 105 fixed roller so as to permit the mop to be readily inserted within the receptacle or placed in position against the fixed roller. In the present instance each of the outer brackets 16 is shown as formed upon its inner 110 face with a groove 21 designed to receive one of the reinforcing bands extending around

the pail. It will also be observed that the outer end of the foot piece 15 is formed with the upwardly extending flange 22 which operates to prevent the foot of the operator 5 from slipping off from the foot piece. For the purpose of holding the pail in a steady position when passing downwardly upon the foot piece 15 or bringing the rollers into a coöperative relation to each other, a stationary foot piece 23 is rigidly connected to the bottom of the pail upon one side thereof and is designed to extend outwardly over the floor or other support upon which the receptacle may be positioned.

15 In the operation of the wringer the mop cloth is placed against the fixed roller 2, the guide flanges 7 serving to engage the sides of the mop cloth and to guide the mop into the proper position. The operator then places 20 one of his feet upon the stationary foot piece 23 while with the opposite foot he presses downwardly upon the foot piece 15 until the movable roller 10 bears against the mop cloth with the required degree of pressure according 25 to the dryness to which it is desired to wring the mop. An upward pull upon the mop then draws the mop cloth through the two rollers in such a manner as to wring the same. In this connection it is desired to call 30 attention to the fact that the movable roller 10 bears against the upper portion of the fixed roller and this arrangement of the parts facilitates the wringing of the mop when pulling the same upwardly and also causes the 35 pressure exerted by the movable roller against the fixed roller to aid in maintaining the receptacle in a steady position.

The inner brackets both serve to guide the mop into position against the fixed roller and 40 to prevent the mop from passing around the ends of the roller and winding about the spindle. The method of mounting the movable roller so that it engages with the upper surface of the fixed roller brings about a 45 powerful downward pressure which is in a direct line with the foot piece, instead of a weak side pressure. The manner of mounting the rollers also facilitates the locating of the bail in the proper position to maintain 50 the center of gravity and thus keep the pail level while being carried.

In securing the outer brackets 16 to the pail 1 either bolts or wood screws may be

utilized although the latter are for many reasons preferable since they do not extend 55 entirely through the pail and there is less liability of leakage. As shown in the drawings three wood screws are employed, the middle screw being lowered below the end screws so as to be out of alinement therewith. 60

Having thus described the invention, what is claimed as new is:

1. In a mop wringer, the combination of a receptacle, inner brackets applied to opposite sides of the receptacle, the said inner 65 brackets being each formed at one end with an inwardly projecting guide flange, and at the opposite end with an outwardly projecting wing designed to engage the edge of the receptacle, a fixed roller journaled between 70 the brackets at points immediately below the wings and in coöperative relation to the guide flanges, a movable roller, and means for bringing the movable roller into coöperative relation with the fixed roller. 75

2. In a mop wringer, the combination of a receptacle, inner brackets applied to opposite sides of the receptacle, the said brackets being provided at one end with wings designed to engage the edge of the receptacle 80 and at the opposite end with lateral guide flanges, ears being provided which project upwardly from the brackets, said ears being designed to engage a bail, a fixed roller journaled between the brackets at points below 85 the wings, a movable roller, and means for moving the movable roller into coöperative relation with the fixed roller.

3. In a mop wringer, the combination of a receptacle, inner brackets applied to the receptacle, each of said inner brackets being provided at one end with a wing designed to engage the edge of the receptacle, and at the opposite end with a lateral guide flange and also with means for engaging a bail, a fixed 95 roller journaled between the brackets in coöperative relation to the guide flanges, a bail engaging the brackets, a movable roller, and means for bringing the movable roller into coöperative relation with the fixed roller. 100

In testimony whereof I affix my signature in presence of two witnesses.

WILLOUGHBY MOFFAT. [L. S.]
